UNITED STATES PATENT OFFICE.

LEWIS T. HOUGHTON, OF WORCESTER, MASSACHUSETTS.

SPINNING OR TWISTING FRAME.

No. 879,642.

Specification of Letters Patent.

Patented Feb. 18, 1908.

Application filed October 29, 1906. Serial No. 340,990.

To all whom it may concern:

Be it known that I, LEWIS T. HOUGHTON, a citizen of the United States, and resident of Worcester, county of Worcester, and State of Massachusetts, have invented an Improvement in Spinning - Frames or Twisting-Frames, of which the following description, in connection with the accompanying drawing, is a specification, like letters on the drawing representing like parts.

This invention relates to spinning frames or twisting frames.

Spinning frames or twisting frames are commonly made with top-roll saddles, one of which bears on the top rolls of each set of drawing rolls and each of which has suspended therefrom by means of a stirrup a weighted lever, the purpose of which weighted lever is to apply the necessary pressure to the saddle and thus to the top-drawing rolls. These top-drawing rolls, or "top rolls" as they are usually termed, are generally covered with leather or some similar material, and in order to properly perform their function they should be perfectly cylindrical. Whenever the spinning or twisting frame is idle, the pressure on the top rolls due to the weights carried by the weighted levers is very apt to cause the surface of the rolls where they touch each other to become flattened somewhat, and if this pressure is applied to the surface of the rolls on one place for a considerable length of time, the flat places on the rolls are likely to become permanent. When this occurs the efficiency of the rolls is materially affected. In actual practice the working hours of the day in which the drawing rolls of the spinning or twisting frame are in use constitute only about thirty-five per cent. of the entire time, and the remaining sixty-five per cent. of the time the rolls are idle and the weights of the weighted levers are bearing on the rolls in one place, thus tending to cause the flat places above mentioned. For these reasons it is desirable to have the pressure removed entirely from the top rolls whenever the spinning or twisting frame is idle whether it be for a longer or shorter period, but in practice it has not been customary to remove the weight from the top rolls during the night because as such spinning or twisting frames are now constructed, the only way in which the weight could be relieved from the top rolls was by lifting each individual weight separately off from its

weighted lever. This course involves a good deal of labor owing to the large number of weighted levers in spinning frames as usually constructed and also is something of a difficult operation because of the position of the weights and the amount they weigh.

One of the objects of my invention is to provide a novel construction by means of which the pressure or weight on all the top-roll saddles may be simultaneously relieved by one operation and without the necessity of handling the weights individually.

My invention also contemplates a novel arrangement by which the controller for the driving mechanism is locked against movement when the weight is relieved from the top roll saddles, and the weight-relieving mechanism is locked when the driving mechanism is operated.

The particular features wherein my invention resides will be more fully hereinafter described and then pointed out in the claims.

In the drawings wherein I have shown some embodiments of my invention merely for the purpose of illustrating the principle thereof, Figure 1 is a top plan view of a portion of a spinning frame or twisting frame to illustrate the application of my invention thereto, said view showing one form of my invention; Fig. 2 is a vertical section showing the drawing rolls, one weighted lever and in cross section the weight-sustaining member; Fig. 3 is a front view of one means for relieving the weight from the top-roll saddles; Fig. 4 is a back side view of Fig. 3; Fig. 5 is a section on the line x-x, Fig. 4; Fig. 6 shows a different form of weight-relieving mechanism; Fig. 7 is a side view of a portion of Fig. 6; Fig. 8 is a detail of the interlocking mechanism.

I have not attempted to show in the drawings a complete spinning or twisting machine, but only a sufficient portion of one to illustrate the principle of my invention.

The frame of a spinning and twisting machine of any suitable type is shown at 3, and this carries the driving mechanism herein shown as a driving shaft 4 by which the drum for driving the spindles (not shown) and the drawing rolls 6 are driven. The driving shaft may be operated in any usual way, and as illustrating one way, I have shown it as having thereon the usual fast and loose belt driven pulleys 7 and 8. The controller for setting the driving mechanism in operation and for

throwing it out of operation is herein shown as a belt shipper 9 for shifting the belt from one to the other pulley for starting and stopping the machine. This belt shipper is carried by a shipper-rod 10, as usual, which extends longitudinally of the frame and which has a laterally-projecting arm 11 fast thereto, the outer end of which arm has a pin-and-slot connection with a crank-arm 12 extending from a vertically-arranged shaft 13. This shaft 13 is usually provided with a handle by means of which it may be turned manually, the turning of the shaft operating through the crank 12 and arm 11 to shift the shipper-rod 10, as will be obvious, and thus to start or stop the machine.

Resting on the top rolls 6 is the usual top saddle 14 from which is suspended a stirrup 15 that supports at its lower end a weighted lever 16, one end of said lever being fulcrumed on the fulcrum 17, and the other end carrying a weight 18 by means of a suitable link or suspender 19.

The parts thus far described are such as are usually found in spinning frames or twisting frames and form no part of my present invention.

The weights 18 for the various top roll saddles are independent from each other and where no device is employed to relieve all the top roll saddles simultaneously from the pressure of the weights, each weight has to be removed separately and independently if for any reason it is desirable to take the pressure off from the top rolls. This individual lifting and handling of the weights is a rather difficult operation and obviously requires considerable time.

Various devices have heretofore been suggested for simultaneously relieving all the top roll saddles of the weights, and my invention contemplates a novel means for accomplishing this object. In accordance with my invention as herein illustrated I place beneath the weighted ends of all of the levers on either side of the machine a movable weight-sustaining member or bar which when moved into operative position engages the weighted ends of the levers and elevates them with their attached weights, thereby relieving the top-roll saddles of pressure. In the form of the invention illustrated this weight-sustaining member is a vertically-movable one, but it might be mounted to swing from its inoperative to its operative position without departing from my invention. In the drawings this weight-sustaining member or bar is designated by 20, and it is situated beneath the weighted ends of the lever 16 on either side of the machine and closely adjacent to but in front of the suspenders 19. It may be guided in its vertical movement by any suitable means, and as herein shown, I have provided at each end and may provide at intermediate points if desired, a guide-member 21

which is secured to the frame 22 of the machine and which is provided with the slot 23 in which the bar or member 20 is received, said slot acting to guide the member in its vertical movements. The guide-member 21 is herein shown as having a back portion 25 from which extend the two flanges having the slots 23 therein, and it may also be provided with feet 26 which rest on and are secured to the frame 22. The body 25 is shown as extending down through the slot 27 in the frame 22.

The necessary vertical movement of the weight-sustaining member 20 may be secured in various ways without departing from the invention, it being only essential that it have sufficient vertical movement to take the weights 18 off from the top-roll saddles.

In Figs. 2, 3, 4 and 5, I have shown a lifter 24 which is received between the flanges 21 of the guide, and which is provided with the hook portion 28 to hook under the lower edge of the bar 20. This lifter 24 is provided with a stem or shank 29 which is bent over the top of the support 25 and which is secured to one member 30 of a toggle-lever, the other member 31 of which is pivoted to the lower end of the body 25, as best seen in Fig. 3. The straightening of the toggle-lever, as shown in dotted lines Fig. 4, obviously results in raising the lifter 24, and such action will lift the bar or weight-sustaining member 20 thereby to swing the levers 16 into the dotted line position Fig. 2.

I propose to employ a lifter for each of the guides 21 and to provide means for elevating all the lifters simultaneously, and in the form of the invention shown in Figs. 2 to 5, this is accomplished by connecting all the toggle joints to an actuator 33 which extends longitudinally of the machine, whereby when the actuator is moved all the toggles are straightened thereby elevating all the lifters. The connection between the actuator and the toggle levers may be made in any suitable way. One convenient way is to extend each of the members 31, as at 32, to pass through an aperture 33 in the actuator, but my invention is not limited to such construction.

These spinning frames are usually double, that is, they have a series of drawing rolls on each side thereof, and therefore in equipping such a machine with my invention, I would employ two weight-sustaining members 20 and two actuators 33, one at each side of the machine, as seen in Fig. 1. I also propose to connect the two actuators 33 for simultaneous operation, and in the present embodiment of my invention, I do this by connecting each to a cross-head 34 which is situated at one end of the frame and which is adapted to be moved longitudinally of the frame by any suitable means. The device herein shown for operating the cross head and actuators is a screw 35 which plays in a nut 130

- (not shown) fixed to the cross-head, which screw may be operated by a suitable hand-wheel 36 or crank. With this construction, it will be seen that by moving the cross-head 5 in the right direction, all the lifters will be raised, thereby to elevate the outer ends of all the lifters 16 and thus at one operation to relieve the weight or pressure from all of the top-roll saddles.
- 10 In Figs. 6 and 7, I have illustrated a slightly different means for raising the weight-sustaining member 20, and in this form of the invention, I employ a plurality of swinging arms 40, each pivoted at its lower 15 end, as at 41, either to the frame or to a bracket 42 depending from the frame, and each carrying at its upper end a roll 43 which is situated underneath the weight-sustaining member 20. The various swinging arms 40 have a pin-and-slot connection with an actuator 33 so that by moving the actuator longitudinally of the frame, the swinging arms 40 may be moved from their inclined position shown in full lines Fig. 7 to their 20 vertical position shown in dotted lines Fig. 7, and obviously during their movement from the inclined to the vertical position, they will engage and elevate the weight-sustaining member 20, thereby forcing it against the lever 16 and elevating the outer ends thereof, as will be obvious. Other ways of simultaneously elevating the weighted ends of the levers 16 may be adopted, however, without departing from the invention.
- 25 In the present embodiment of my invention I have also provided for locking the device or other means for operating the weight-relieving mechanism when the belt is running on the fast pulley 7 or in other ways 30 when the driving mechanism is operated, and have also provided means for locking the controller or shipper mechanism with the belt running on the loose pulley 8 whenever the weight-relieving mechanism is thrown 35 into operation for relieving all the weights.
- The device for operating the weight-relieving mechanism is herein shown as the hand wheel 36 and for locking said hand wheel I have provided a locking bolt 48 40 ably mounted in a frame and having one end shaped to be engaged by the arm 11 so that when the shipper-rod and the arm 11 are moved toward the left Fig. 1 to shift the belt to the fast pulley 7, said arm 11 engages the locking bolt 48 and moves the outer end thereof into locking engagement with the hand-wheel 36. This locks the weight-relieving mechanism so that the latter cannot be operated until the belt shipper has been 45 moved toward the right Fig. 1 to carry the belt to the loose pulley 8.
- Any suitable means may be employed for retracting the locking bolt 48 from the wheel 36 when the belt-shipper is moved to shift 50 the belt to the loose pulley. In the illus-

trated form of my invention I connect said bolt 48 to the arm 11 by means of a chain 71 or other flexible connection so that the bolt is retracted by the movement of the shipper-rod. The movement of the shipper-rod is greater than necessary to shift the locking bolt 48, and if desired I may make the flexible connection 71 of such a length that it will not draw on the locking bolt to release the latter until the belt is nearly 75 shifted on to the loose pulley. With this construction the locking bolt will not be entirely withdrawn until the belt is fully shifted. On the other hand, when the belt shipper is moved to the left Fig. 1 the first part 80 of the movement thereof has no effect in moving the locking bolt and the latter will not be thrown into operative position until the belt has been fully shifted on to the tight pulley.

In order to lock the belt shipper when the weights are relieved, I have in this embodiment of my invention pivoted to the frame of the machine a locking pawl 51, see Figs. 1 and 8, one end of which lies over one end of 85 one of the weight-sustaining members 20, the other end of which is adapted to engage a locking notch 52 in the shipper-rod 10. The shifting of the belt to the loose pulley by the belt shipper brings the locking notch 52 90 in line with one end of the locking pawl 51, and when the weight-sustaining members 20 are elevated, as above described, one of them acts against the locking latch 51 and turns it about its pivot 53 to cause the end thereof 95 to enter the locking notch 52 and thus lock the shipper-rod 10.

When the weight-sustaining member is lowered again the locking pawl 51 will be retracted by its own weight or a suitable 100 spring may be used for this purpose.

It is not essential to my invention that both the actuators be operated simultaneously although I prefer such construction.

Having fully described my invention, what 110 I claim as new and desire to secure by Letters Patent is:

1. In a spinning or twisting frame, the combination with a plurality of top-roll saddles and weighted levers therefor, of a weight-sustaining bar situated beneath all of the levers closely adjacent to the weighted ends thereof, and an actuator for elevating both ends of said bar in unison thereby to relieve the top rolls from pressure.

2. In a spinning or twisting frame, the combination with a plurality of top-roll saddles, of levers connected thereto, weights suspended from the ends of the levers, a weight-sustaining bar situated beneath all said levers 125 adjacent to but in front of the weights, and an actuator for elevating both ends of said bar in unison.

3. In a spinning or twisting frame having in combination a plurality of top-roll saddles,

130

- weighted levers therefor, a weight-sustaining bar situated beneath the weighted levers, swinging arms for raising said bar and means to operate said arms in unison.
5. 4. A spinning or twisting frame having in combination a plurality of top-roll saddles, weighted levers therefor, a weight-sustaining bar situated beneath the weighted levers, swinging arms for raising said bar, said arms 10 being pivoted to a fixed support, and means to operate said arms in unison.
5. In a spinning or twisting frame, a series of top-roll saddles on each side thereof, weighted levers for said saddles, in combination with two weight-sustaining bars one situated beneath the weighted levers for each series of saddles, and means to raise said bars simultaneously.
6. In a spinning or twisting frame, a plurality of top-roll saddles and weighted levers therefor in combination with a weight-sustaining bar situated beneath the levers, and means for elevating said bar comprising an actuator extending longitudinally of the 25 frame and adapted for movement in the direction of its length.
7. In a spinning or twisting frame, a plurality of top-roll saddles and weighted levers therefor, in combination with a weight-sustaining bar situated beneath the levers, and means to elevate said bar comprising swinging arms and an actuator extending longitudinally of the frame and adapted for longitudinal movement.
- 30 8. In a spinning or twisting frame, a plurality of top-roll saddles and weighted levers therefor, in combination with a weight-sustaining bar situated beneath said levers, a plurality of swinging arms operatively connected to said bar, and an actuator movable longitudinally of the frame for swinging said arms thereby to elevate said bar.
9. In a spinning or twisting frame, a series of top-roll saddles on each side thereof, and weighted-levers for said saddles, a weight-sustaining bar on each side of the frame situated beneath the levers on each side, swinging arms operatively connected to each bar, an actuator for each set of swinging arms, and means to operate said actuators simultaneously.
10. In a spinning or twisting frame, a plurality of top-roll saddles on each side thereof and weighted-levers for said saddles, in combination with a weight-sustaining bar situated beneath the levers on each side of the frame, a longitudinally-extending actuator for each bar, and means to operate said actuators in unison.
11. In a spinning frame, the combination with top rolls, of driving mechanism therefor, a controller for the driving mechanism, a weighted top roll saddle, a weight-sustaining member to relieve said saddle of its weight, a device for operating said weight-sustaining member, means to engage and lock said device from movement when the driving mechanism is operative, and other means to engage the controller and lock it from movement when the weight-relieving mechanism is operative.
- In testimony whereof, I have signed my name to this specification, in the presence of two subscribing witnesses.
